CLAIM

The ornamental design for a cover for a lollipop, substantially as shown and described.

DESCRIPTION

FIG. 1 is a perspective view of a cover for a lollipop showing my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view of the cover for a lollipop of FIG. 1.

The broken lines showing of the stick and wrapper in FIGS. 1-5 are included for the purpose of illustrating unclaimed portions and form no part of the claimed design.
